UNITED STATES PATENT OFFICE.

CLARENCE T. MAPES, OF CRAFTON, PENNSYLVANIA.

UNDERREAMER.

1,165,196..

Specification of Letters Patent. Patented Dec. 21, 1915.

Application filed February 17, 1912. Serial No. 678,355.

To all whom it may concern:

Be it known that I, CLARENCE T. MAPES, a resident of Crafton, in the county of Allegheny and State of Pennsylvania, have invented certain new and useful Improvements in Underreamers, of which the following is a specification.

This invention relates to an underreamer of the general type illustrated in Letters Patent No. 923,677, granted to me June 1, 1909, wherein the reamer body is recessed upwardly from its lower extremity to receive and confine the shanks of a pair of opposed slips, the shanks being movable vertically and tilttable within the body cavity to permit the slips to expand into cutting position and to be contracted from such position. In this type of underreamer the slip shanks are so confined within the body cavity as to firmly brace and hold them in position to resist the excessive strains to which the slips are subjected when in action. It is necessary to keep the body recess clear of drillings, dirt, etc., so that the slips may move with certainty and accuracy into and out of cutting position. At the same time the construction should be such as to afford ready entrance of the slip shanks into the holding and bracing socket or cavity. It is also desirable to avoid as far as possible the formation of irregularities in the coöperating surfaces or faces of the socket and the slips, such surfaces being difficult to form and tending to cramp and obstruct the slips, especially in the presence of drillings, and other foreign matter that may work into the slip confining cavity.

With the foregoing requirements in view, one object of the present invention is to provide for closing the space between the opposed slips when the latter are in cutting position, the closing means being removable so that the insertion and removal of the slips is not obstructed.

A further purpose is to provide the body recess and the slips with surfaces that are substantially smooth or unbroken, i. e., without offset depressions or projections so that said surfaces may be readily formed, also that there is no tendency for the slips to cramp, or to be obstructed by accumulations of sand, etc., which surface irregularities when present are liable to induce.

In the accompanying drawings, Figure 1 is a vertical section of the underreamer with

the parts set for cutting, and Fig. 2 is a similar view with the parts contracted, as when being lowered or raised in a well casting. Fig. 3 is a side elevation of the reamer with the slips expanded into cutting position. Fig. 4 is a sectional elevation on line 4-4 of Fig. 3. Fig. 5 is a detail view of one of the slips. Fig. 6 is an inverted end view of the reamer body. Fig. 7 is a sectional plan on line 7-7 of Fig. 1. Fig. 8 is an elevation of the lower portion of the body and the slips, showing abutting surfaces of different form than those illustrated in Figs. 1, 2 and 3.

Referring to the drawings, 2 designates the body of the underreamer having the usual pin 3 at its upper end for connecting with a string of tools. The body is recessed upwardly from its lower end to form a laterally closed cavity 4 for confining the slips. The cavity 4 is of substantially the form illustrated in my above mentioned patent, the upper portion thereof being circular in cross-section at 5, and from this upper circular portion the cavity widens downwardly into substantially oval form, the opposite narrower walls 6 having offsets 7 to receive the slip shank extremities, as will be presently described. The wider walls 4' of cavity 4 are smooth, being uninterrupted by depressions or guideways, such as are shown in my former patent, and in the present construction guide flanges on the slips as illustrated in said patent are omitted, so that the faces of the slips and the cavity walls are smooth and there is no opportunity for drillings or dirt to collect, nor tendency on the part of the slips to cramp. Also, the omission of such irregular features simplifies and facilitates manufacture of the parts, and this feature will be especially appreciated when it is remembered that the tool body and slips are usually formed of steel.

The pair of opposed slips 8 have their shank portions 9 entered in body cavity 4, the adjacent faces of the slips being recessed at 10 to receive the T-head end 11' of rod 11, which latter extends upwardly through bore 12 of the body, with spring 13 confined theron as in my said former patent. The slip shanks 9 are of a form to readily enter cavity 4 when the latter is unobstructed, and are of such shape as to move vertically therein and also tilt as is required

for spreading the slips into cutting position and for retracting them so that they may pass within the wall casing. The upper extremities 9' of the shanks are shaped complementary with the top wall 4" of cavity 4, so that when the slips are raised and extended, as in Fig. 1, their upper extremities accurately fit the circular upper portion 5 of cavity 4. When the slips are lowered 10 and tilted into the contracted position shown in Fig. 2 for entering the casing, shank extremities 9' enter the cavity offsets 7, as shown in Fig. 2. The surfaces of the slip shanks are of such form as to accurately fit 15 the walls of cavity 4 when the slips are in the set position shown in Fig. 1, the rounded outer edges 9" of the shanks fitting the narrower curved walls 6 of cavity 4, and the substantially flat side faces of the shanks 20 fitting smoothly against the uninterrupted wider walls 4.

Abutments 14 at the juncture of the slip body and shanks are disposed at angles complementary with the lower extremity 14' of body 2 surrounding cavity 4. In the adaptation of Figs. 1 and 2 these abutting surfaces converge inwardly and downwardly toward the center of the tool, although they may converge inwardly and upwardly, as in 30 Fig. 8.

Slip shanks 9 are of such size and shape that when embracing the headed rod 11 they may be readily entered within cavity 4 when the latter is wholly unobstructed. It is desirable, however, to close the space between the shanks when the slips are in cutting position, thereby preventing dirt from entering between the shanks and lodging in cavity 4. To accomplish this I provide a 40 removable bridging member which is put in place after the slips are inserted and which is embraced by them, said member closing the intervening space when the slips are set for cutting, and also holding the slips against complete withdrawal from the body cavity. In the present adaptation, this bridging member is circular in cross-section and may take the form of a roller 45 which is removably held by the transverse pin 16, the pin extending through apertures in the, depending abutment-forming portions 17 at opposite sides of the lower extremity of body 2. In addition to excluding drillings, etc., said member combines with abutments 17 in providing backing surfaces clear across the reamer body 50 for the slip faces 18. The adjacent faces of shanks 9 are oppositely recessed at 19 to embrace when contracted the cross member 55 15, and with the latter of curved form recesses 19 may be formed by drilling, thereby avoiding tedious and expensive milling. The transverse member is not in the way, 60 the slips closing compactly therearound as 65 in Fig. 2, and at the same time said mem-

ber renders it quite impossible for the slips to drop out as would occur if rod 11 should break or become disengaged from the slips.

By the use of the circular or rounded bridging member with the complemental 70 configuration of recesses 19, it will be seen that when the slips are in their lower position, a maximum surface contact is had between said member and the slips. This extended surface contact of member and slips 75 is not materially affected at the beginning of the slip-elevating movements, due to the operation of the inclined faces 7 on the upper ends of the slips, so that at the time when the elevating movement begins the 80 stress is somewhat distributed over these contacting surfaces, the surface contact decreasing after such start has been had and being substantially minimum when the slips are expanded or in their elevated position. 85 As will be obvious, this tends to decrease localization of wear on the slips. Furthermore, the making of this device in the form of a roller not only enables a replacing action to be provided, but any tendency of 90 one or the other slips to stick during the movements of the slips would tend to shift the roller on its axis and thus present a new surface, thereby tending to decrease the effect of wear on the bridging member. 95

I claim:

1. The combination of a reamer body having its lower end formed with an upwardly extending laterally closed cavity substantially oval in horizontal cross-section with the opposite horizontally longer walls of the cavity flat and uninterrupted and unindented from the bottom to the top of the cavity and with the opposite end walls of the cavity curved, a device removably bridging the lower end of the cavity at the center thereof and supported by the said opposite flat side walls, a pair of opposed slips shouldered at their outer sides between their ends to provide ledges for engaging the lower extremity of the body when the slips are contracted, the portions of the slips above the shoulders formed with uninterrupted and unindented flat side faces complementary with the flat side walls of the body recess 115 and the other outer surfaces of said slip portions rounded complementary with the rounded walls of the recess, the opposed inner faces of the slips having recesses complemental to and adapted to embrace the 120 said bridging device when the slips are lowered and contracted, said device and the complemental recesses having configurations tending to provide a decreasing surface contact therebetween during elevating movements of the slips, the wall of the body recess and the slips shaped to cause the lower portions of the slips to expand when elevated and to contract when lowered, and 125 slip operating means. 130

2. The combination of a reamer body having its lower end formed with an upwardly extending laterally closed cavity substantially oval in cross section, the body formed at opposite sides of the smaller diameter of the cavity with downward extensions which provide lateral abutments and with the portions of the body extremity between said extensions comprising vertical abutments, a pair of opposed slips shouldered between their ends to provide ledges which engage the vertical abutments formed by the body extremity, the adjacent faces of the slips formed with transverse surfaces which intersect the ledge-formed surfaces and which are adapted to engage the lateral abutments formed by the body projections whereby the slips are reinforced by the vertical and lateral abutments in substantially the same transverse plane, a device removably secured between the body projections and constituting continuations of the abutment-forming surfaces of the latter thereby providing an uninterrupted transverse abutment for each slip from side to side thereof, the portions of the slips above the said shoulders forming shanks having flat sides and curved ends which fit the body recess, the adjacent faces of the shank portions recessed so that when lowered and contracted they embrace the removably inserted device with the latter preventing complete withdrawal of the slip shanks from the body re-
- cess, the wall of the body recess and the slip shanks shaped to cause the depending portions of the slips to expand when elevated and to contract when lowered, the slip surface-contact with said device decreasing during the elevating movements of the slips, and slip operating means. 35
3. The combination of a reamer body recessed upwardly upon its lower end with the recess closed laterally, a pair of opposed slips having shank portions movable vertically and tilttable within the cavity for moving into and out of set position, the slip shanks being of a size to enter the body cavity when the latter is unobstructed and with the adjacent faces of the slip shanks formed with opposite curved recesses, a roller removably mounted transversely within the body cavity between the slips and adapted to be embraced by the opposite curved depressions in the adjacent faces of the slip shanks, the surface contact of roller and slips decreasing during the elevating movements of the slips to provide a minimum contact when the slips are in elevated position, and slip operating means. 40 45 50 55
- In testimony whereof I affix my signature 60
in presence of two witnesses.
